UNITED STATES PATENT OFFICE.

HEINRICH WILHELM STEDLER, OF LÖSSNITZ, ERZGEBIRGE, GERMANY.

MANUFACTURE OF SHOES.

1,359,847.

Specification of Letters Patent. Patented Nov. 23, 1920.

Application filed July 8, 1916. Serial No. 108,202.

To all whom it may concern:

Be it known that I, HEINRICH WILHELM STEDLER, a subject of the German Emperor, and a resident of Lössnitz, Erzgebirge, Germany, have invented certain new and useful Improvements in the Manufacture of Shoes; and I do hereby declare the following to be a full, clear, and exact description of the invention, reference being had to the accompanying drawings, in which—

Figure 1 is a side view of a portion of a shoe as being made according to my invention,

Fig. 2 is a bottom plan of a shoe in course of manufacture according to one form of my invention,

Fig. 3 is a plan view of shoe in course of manufacture similar to that used in Fig. 1,

Figs. 3^a and 3^b are sectional views showing modifications of abutments used,

Figs. 4 and 5 are sectional elevations showing manner of sewing parts of the shoe together and the machinery used therefor,

Fig. 6 is a perspective view of a finished front tip,

Fig. 7 is a perspective view of a finished upper without the tip,

Fig. 8 is a view showing an inner sole with a steel plate for use in pointed shoes, or for shoes with a high spring or a high heel,

Fig. 9 is a longitudinal vertical section of Fig. 8,

Fig. 10 is a vertical section of a shoe upper showing the inner sole of Fig. 8 introduced into the upper.

In the methods used hitherto for manufacturing shoes it was customary to form an upper of a shoe from flat parts of soft leather and to pinch or last it over a last whereby the upper of the shoe was brought to a shape similar to that of the last. This practice has of late met with considerable difficulties owing to the modern requirements as to the exterior appearance of the shoes and because stiffening linings became necessary or were used for maintaining the shape of the shoes, particularly at the tip.

Hitherto a junction with the inner sole was not possible without the difficult pinching or lasting work and even then it could

only be effected after the shoe had again dried after the moistening required for the pinching work.

The uniformity of the shoes was dependent on the tensibility of the leather. If the leather had an unequal tensibility and no damage was to occur to the appearance of the shoes, this caused a too tight or too loose pulling over, *i. e.* a too tight stretching of the upper in longitudinal direction and resulted in the first case in torn or cracked tips and in the latter case in folds or wrinkles at the front tip, the elimination of which was in both cases a great drawback in the manufacture.

According to my invention I first mold the front tip over the stiffening lining *n* and fasten it by glue. Hereby the tip *i* obtains the shape or fashion of the last exactly. The inwardly turned flange *k* forms a flat seaming-lap for the connection to the innersole.

The finished front tip *i* is then united with the upper *aa* according to the dotted line *s* in Fig. 7, or it is stitched in the same way to the vamp *a* before connection of same to the upper. Whether the shoes are to be with or without a tip *i* it is essential to fix the front part of the vamp so that it will effect the upper *aa* as shown in Fig. 1, substantially as described. Along the seaming lap *k* of the upper a shoulder *b* is provided consisting of a cord or any other suitable means.

After this preparation the upper is fastened to the innersole by stitches or any other suitable fastening means. This process is done without the use of any last exclusively by guides. In this fastening or stitching operation the innersole is guided by an edge guide *f* Fig. 4 provided on the machine, and a process similar to the pinching or lasting is caused now by the action of the presserfoot against the shoulder *b* provided on the upper. When sewing and thus pressing or pulling down the upper leather by the presser foot of the machine the shoulder *b* draws the upper leather in the arrow direction as shown in Fig. 2 inwardly, the welting *d* being fastened by the same stitches by means of a guide in the presserfoot which

feeds the welt in a flat and natural way so that any compression or expansion of said welt is excluded.

In very pointed or ladies' shoes the shoulder *t'* Figs. 8 and 9 of the steelplate, temporarily attached to the innersole, can be used as a guide in the fastening or stitching operation instead of the guide *f* Fig. 4 provided on the machine. For this purpose 10 and for the purpose of giving the innersole the wanted spring for a low or high heel a sinuous curved steel plate of smaller size than the innersole is used (Figs. 9 and 10). In using the edge *t'* of the steelplate as a 15 guide the seaming-lap *k* of the upper has to cover the edge part of the innersole not covered by the steelplate, whereby the action of the fastening machine remains as described.

20 By employing the shoulder *t'* of the steelplate exclusively as a guide in the fastening operation the shoulder *b* attached to the upper may be avoided and the feeding or inward drawing of the upper-leather to the 25 edge guide *t'* be done manually.

The pulling over or tight stretching of the upper in the longitudinal direction is usually effected by the introduction of the last into the so formed shoe-casing before fastening the heel part and thus stretching the upper longitudinally before the heelpart is united with the innersole. But on the other hand the heelpart can also be treated like the front part of the shoe and thus the shoe can 35 be sewn all around in position.

If desired this method may also be employed without the frame according to which final method either "welt" or "McKay" the shoes are now to be finished.

40 The manufacture of shoes according to my invention presents great practical and economical advantages. The time required for manufacturing the shoes is considerably shortened as the lasting or pinching process 45 and the wet treatment combined therewith are omitted. The expensive lasting, pulling-over and welting machines are unnecessary; and a considerable saving of work, workmen and material is obtained and great 50 waste is avoided.

On the vamp *a* of the upper *aa* of the shoe is fixed by means of a seam *o* a shaped or molded front tip *i*, as shown in Fig. 1. On the front tip *i* is to be seen on the lower side 55 the turned in flange or seaming lap *k*. Along this turned in flange of the vamp is fastened by sewing the abutment or shoulder in the shape of a cord *b*.

Fig. 2 shows a shoe in the course of manufacture seen from below, with the innersole *c* and the welt *d*. The parts are already 60 united together by seams *p*.

Fig. 3 shows the shoe ready sewn. The cord *b* which has been used only while sewing, has now been removed and the heelpart, 65

has been fastened. The turned in flange *k* is now also clearly to be seen laterally.

Figs. 4 and 5 show two different sections of the arrangement of the machine used for my improved method, together with the 70 parts of the shoe to be manufactured.

The needle-plate *e* is provided with a guiding edge *f* for the innersole *c*. Passing over the innersole and the guiding edge lies the upper or vamp *a* with its shoulder *b* on 75 the border. The welt *d* engages the cord *b* and on the welt rests the presserfoot *g* of the machine.

As will be seen in Fig. 5, the presserfoot is provided with a guide *h* for the welt *d*. 80

If, necessary, the presserfoot could go down as far as the upper in order to favorably influence the effect upon the shoulder or the cord *b* or the like substitute.

Fig. 6 shows a front tip *i* consisting of 85 the upper-leather *l* and a stiffening lining *n*. The front tip has been shaped in its upper part to suit the last or it has been given a proper shape, as shown by shading in the drawing, and has in its lower part a 90 flat flange *k* bent inwardly. Owing to its qualities the stiffening lining *n* is capable of maintaining and holding the shape as well as the flange after a single pressing in the molding-operation. The upper-leather *l* is 95 covered before the molding operation with a suitable glue and is thereby maintained on the shaped tip. On account of the ductility and the thin layers of both the materials *l* and *n* any formation of bulged parts by 100 the applied pressure is avoided.

Fig. 7 shows an upper *aa* of a shoe, ready with the exception of the front tip. The inner lining *m* is bent backward to allow both edges *r* to project, by means of which 105 the ready shaped front tip *i* is sewn to the proper place by a column-machine, as shown by the dotted line *s*.

In the sewing operation for uniting the upper, the innersole and the welt, the upper 110 of the shoe is drawn by the presserfoot inwardly in the direction of the arrows shown in Fig. 2, just as it would otherwise occur in the pinching or lasting operation. But the substantial feature consists herein that 115 this inward-drawing or pressing is performed by the employment of the guides (*f* or *t'*) solely in the sewing or fastening process and by the respective part of the sewing or fastening machine.

The abutment or shoulder *b* (for the presser foot) by which the upper part is drawn inwardly as described, could also be formed by other means than by a sewn on cord. For instance the leather could be provided at certain intervals or points with clips which could afterward be easily removed, as 125 shown in Fig. 3^a.

The upper could also be turned or bent around and the bent part be fixed tempo- 130

rarily, as shown in Fig. 3^b. It is only essential to use means which during the sewing operation allow the presserfoot to catch hold of the upper and to draw it inwardly, 5 as described.

For shoes with a high spring, the execution shown in Figs. 8 to 10 is applied.

Fig. 8 shows a top view of the innersole *c* with a steelplate *t*. This steelplate is provided with clips or points *u* or the like, 10 pressed through at various places and by means of which the innersole is held, as Fig. 9 shows in section. As further shown in Fig. 9, the steelplate *t* has a spring corresponding to the heel to be used for the 15 respective shoe. By laying and pressing the steelplate upon the innersole, this latter which consists of leather or the like, assumes the same spring as the steelplate. 20 The thus elevated innersole is then introduced into the finished upper *aa*, as shown in Fig. 10 and the edge *t'* of the steelplate shown in Figs. 8 and 9, can then be used as 25 a guide in the described stitching operation or for temporarily fastening the upper to the innersole by means of pins *v*, as shown in Fig. 10. After this preliminary fastening the welt can then be sewn on in the previously described way or be left away according 30 to whether the outersole is now to be fastened by the "McKay" or "welt" method.

The assembling by means of the wire pins or tacks *v* would be sufficient to maintain 35 the upper in the proper position until a final assembling with the sole can be effected.

After the uniting operation of upper and innersole or upper innersole and welt, the steelplate is to be removed. In the fastening process as described I would consider it no departure from my invention 40

when using only one of the fastening seams *p* (Fig. 2) or using one of the two seams for connecting the upper to the innersole and the other for connecting the welt to 45 the already united upper and innersole.

I claim:—

1. The method of making shoes having a previously formed tip with an inwardly bent flange or seaming lap, an insole, and 50 an upper, comprising providing an abutment member on the outer edge of the upper, positioning the upper by pressing the abutment inwardly over the bottom of the insole and parallel to the edge thereof, securing the upper and insole together and removing the abutment.

2. The method of making shoes including a previously formed tip, an insole, and an upper, comprising providing an abutment 60 member on the outer edge of the upper, positioning the upper by pressing said abutment member inwardly over the bottom of the insole, securing the upper and insole together, and removing the abutment. 65

3. The method of making shoes having a previously formed tip with an inwardly extending flange or securing lap, an insole, and an upper, comprising providing a detachable flexible abutment member adjacent the 70 outer edge of the upper, positioning the upper by pressing the abutment inwardly over the bottom of the insole and parallel to the edge thereof, securing the upper and insole together, and removing the abutment. 75

In testimony whereof I have signed my name in the presence of two subscribing witnesses.

HEINRICH WILHELM STEDLER.
